STEAM DISTRIBUTION AND CONTROL FOR
LOCOMOTIVES

James C. Maris, Glenolden, Pa.

Application September 24, 1937, Serial No. 165,571

4 Claims.

(Cl. 60—1)

This invention relates generally to locomotives and more particularly to an improved system for controlling supply of steam to simple expansion engine cylinders, the invention being particularly useful in connection with high speed four cylinder type locomotives in which the cylinders are of the simple expansion type.

In the specific disclosure herein, the four cylinder locomotive preferably operates under a high pressure of say, 350 pounds boiler pressure, and in order to provide sufficient continuous tractive power required to operate at a very high speed of say 100 miles per hour with a heavy train, it is necessary to use the high pressure steam economically and expand it down by using relatively large size cylinders, the valve gear cutting off preferably at a very short stroke say 20% to 25%. This will give a low steam and water rate per indicated horsepower.

The necessity for using the steam economically in such a high speed and high power locomotive is because the physical size of a boiler is definitely limited in accordance with the clearance limits required for passing through tunnels, etc., which determine the ultimate size of the boiler. Hence the increase in demand for speed and power cannot be satisfied by increasing the size of the boiler, but must be obtained by operating with maximum economy in the use of steam. This problem, however, is further complicated because the large size cylinders required to operate the engine at higher speeds under the high boiler pressure will produce, during starting, a tractive force sufficient to slip the drivers unless the supply of steam can be very closely controlled. With prior art arrangements, such close control would be difficult to obtain by the engineman because of the extremely close limits within which the throttle valve would have to be cracked. Hence this method of cracking the throttle depends upon the variable personal equations of the engineman and is open to the objection that carelessness in operation or inability to control the valve with the necessary nicety of accuracy will cause the driving wheels to slip and thereby wear the tires and rails as well as placing great strain upon the locomotive mechanism together with other harmful effects on the fire, etc., such as are well known to those versed in the art. Furthermore, the necessary steam control cannot be obtained by a multiple throttle valve because if the engine fails to start upon partial opening of the valve, then steam pressure will gradually build up to the maximum boiler pressure causing slip-

5 with a high degree of sensitivity and accuracy.

Another object is to provide an improved system for controlling supply of steam in a locomotive as above referred to whereby the engine cylinders may be supplied with steam at a maximum possible pressure substantially below boiler pressure and consequently with minimum possibility of slipping the drivers thereby facilitating 10 starting of the locomotive and train, and thereafter allow steam to be supplied to the cylinders under full boiler pressure.

Another object is to accomplish the foregoing objects by a combination of elements constructed 20 and arranged in a manner that is relatively simple and compact and is economical in operation and maintenance.

Other objects and advantages will be more apparent to those skilled in the art from the following description of the accompanying drawings in which:

Fig. 1 is a diagrammatic side elevation of a locomotive embodying my improved control system, parts being broken away to show in elevation 30 certain elements of the control system;

Fig. 2 is a plan view of Fig. 1 but with the boiler removed and a part of the multiple throttle valve broken away, substantially along the line 2—2 of Fig. 3, to show the relation of certain elements 35 in the control system;

Fig. 3 is a longitudinal section through the multiple throttle valve taken substantially on the line 3—3 of Fig. 2;

Figs. 4 and 5 are similar sections taken respectively on the lines 4—4 and 5—5 of Fig. 2;

Fig. 6 is a vertical transverse section taken substantially on the lines 6—6 of Figs. 2 and 3;

Fig. 7 is a side elevation similar to Fig. 1 but showing a modified arrangement of my improved 45 control system;

Fig. 8 is a plan view of Fig. 7 with the boiler removed for purposes of clarity;

Figs. 9, 10, 11 and 12 are longitudinal sections taken respectively on lines 9—9, 10—10, 11—11 50 and 12—12 of Fig. 8.

In the specific embodiments of the invention such as I have disclosed herein merely for the purpose of illustrating two specific forms among possible others that the invention might take, I 55

have provided as shown in Fig. 1 a four cylinder locomotive of the single rigid frame type such as disclosed in McCarroll Patent 1,622,917 wherein a single rigid locomotive frame 1 has a forward 5 pair of cylinders 2 and a rearwardly disposed pair of cylinders 3 located midway between the ends of the frame. The frame 1 is rigidly connected to or formed with said cylinders and is provided with usual pedestals and spring rigging for a forward 10 set of driving wheels 4 and a rearward set generally indicated at 5. Other usual locomotive elements and accessories are, of course, employed but do not enter into my present invention and hence need not be described. Also my invention 15 is applicable to simple expansion articulated type locomotives as well as being applicable to a simple two cylinder locomotive.

A usual boiler 7 is supported in a customary manner upon frame 1 and has a usual steam dome 8 from which steam is conducted through the well known dry pipe 9 to a superheater header generally indicated at 10. As shown in Fig. 4, the superheater header has transversely extending chambers 11 and 12 which are relatively 20 shallow and to which the superheater header tubes are connected in a customary manner but which are not disclosed herein because they do not per se constitute a part of my present invention. Chambers 11 and 12 are separated by 25 a partition 11a having openings 11b to effect uniform distribution to chamber 12. Chamber 12 communicates with another transverse chamber 13, Fig. 3, one end of which communicates with a longitudinal passage 14, Figs. 2, 3 and 6, 30 and thence with a chamber 15, Fig. 3, of an automatic reducing valve mechanism generally indicated at 16. Various types of reducing valves may be employed such as that diagrammatically disclosed herein or that shown in Patent No. 40 855,796, and inasmuch as such devices are well known, further detailed description is not deemed necessary. Steam flows from the valve chamber inlet 15 through a passage controlled by valve 17 to an upper valve outlet chamber 18 and thence 45 into a transverse chamber 19 shown in certain instances in Figs. 3 and 6. The reducing valve 16 is so adjusted and operated in its customary manner that it maintains a constant outlet pressure in chambers 18 and 19 of say 250 pounds 50 as against the 350 pounds boiler pressure.

The remaining steam supply and control structure will be more readily understood from a description of the mode of operation of my improved system. Assuming that the engineman 55 desires to start the locomotive, he rotates a cam-shaft 20, Fig. 6, through a usual throttle lever in the locomotive cab and linkage connected to an arm 21. Inasmuch as such elements are well known, further description thereof is not necessary. Initial rotation of shaft 20 will cause a cam 22 to raise a usual pilot valve 22a to admit 60 low pressure steam from chamber 19 through an opening 19b to a balancing chamber 23. A series of valve plungers 24 are of substantially the same 65 effective area as throttle valves 25 and hence the opposed steam pressure forces acting on the valves and plungers will be substantially balanced. Continued rotation of cam-shaft 20 will cause cams 26 to successively open the throttle 70 valves 25, thereby admitting low pressure steam from chamber 19 into a chamber 27 and thence through an outlet T 28, Fig. 2, to which the usual steam pipes 29 are connected. As shown in Fig. 1, the steam pipes 29 are connected to 75 the forward pair of cylinders through suitable

pipes and joints 31 and to the rear pair of cylinders 3 through pipes 32.

The steam thus supplied to the cylinders is at an appreciably lower pressure than the boiler pressure and at no time can this pressure increase above the maximum possible value of 250 pounds per square inch as determined by the reducing valve 16, and hence it is possible for the engineman to successively open the throttle valves 25 with minimum danger of slipping the 10 wheels and accordingly avoiding wastage of steam. As the locomotive gains speed under the relatively low pressure, a second set of throttle valves 35, Fig. 5, are then successively opened 15 through rotation of a cam-shaft 36 and cams generally indicated at 37. As shown in Fig. 3, the camshafts 20 and 36 are connected by a link 36a for common actuation from the main throttle lever in the locomotive cab although the angular relation of the cams on said shafts is such that 20 the high pressure throttle valves 35 are not initially opened until all of the low pressure valves are open. As the valves 35 open, high pressure steam directly from the boiler flows through chambers 12 and 15 and an opening 37b into a 25 chamber 38 separate from chamber 19, whereby upon opening of valves 35 steam is admitted to a transverse chamber 39. This chamber has free communication with chamber 27, Fig. 6, through an opening 40 in a partition 41, Fig. 3. Hence 30 the chambers 27 and 39 are equivalent to a single chamber communicating with the outlet pipe connection 28 leading to steam pipes 29.

It will be understood that the full boiler pressure now admitted to chambers 39 and 27 will 35 also cause full boiler pressure to build up in chambers 19 and 18, but this will not be detrimental because full boiler pressure already exists in chamber 15 beneath throttling valve 17. Hence there cannot be any reverse flow of high 40 pressure steam in the system after the high pressure throttle valves 35 are open. The high pressure valves 35 are subjected to balancing pressure in a chamber 42 supplied with high pressure steam through a pilot valve 43 which is 45 opened by cam-shaft 36 prior to opening of any of the valves 35.

From the foregoing description it is seen that boiler pressure is automatically reduced in passing through reducing valve 16, whereupon the 50 engineman can readily sequentially open low pressure valves 25 without fear that sudden high pressure will build up in the engine cylinders to cause the drivers to spin. Consequently, there will be no waste of steam or other deleterious 55 effects. After the engine has started, full boiler pressure can be readily supplied to the engine cylinders by sequentially opening the valves 35.

In the modifications shown in Figs. 7 to 12, a pipe 14a corresponding generally to passage 14, Fig. 2, of the preferred form connects into an automatic pressure reducing valve 16a which, like valve 16, maintains a constant reduced pressure on the outlet side thereof. Valve 16a is located outside of the smokebox at a substantially lower 65 level than the superheater header as shown in Fig. 7. A low pressure pipe 18c corresponding generally to chamber 18, Fig. 3, of the preferred form communicates with a chamber 19c. The remaining passage arrangement, valves and operating mechanism therefor are identical to that of the preferred form and hence corresponding parts are given the same reference numerals except that they are primed. The mode of operation is the same, and hence the description of 70 75

the preferred form will suffice for this modification.

From the foregoing disclosure, it is seen that I have provided an extremely simple and yet highly effective throttle control system adapted to insure a convenient and positive means for supplying low pressure steam from the high pressure boiler to the engine cylinders during starting and thereafter supply steam to the cylinders under full boiler pressure. There is no necessity on the part of the engineer to attempt to use exacting control over the throttle valves in an attempt to prevent spinning of the drivers with consequent wastage of steam and in my improved system there is no possibility, in the event the engine does not start immediately upon admission of steam to the cylinders, for full boiler pressure to accumulate in the engine cylinders as would be the case with a usual throttle valve control operated in a cracked position. The automatic reducing valve in my improved system prevents any accumulation of full boiler pressure in the engine cylinders in the event that the engine does not start upon opening of the low pressure throttle valves 25.

It will of course be understood that various changes in details of construction and arrangement of parts may be made by those skilled in the art without departing from the spirit of the invention as set forth in the appended claims.

I claim:

1. In combination, a steam locomotive having a high pressure boiler and simple expansion engine cylinders, a pressure reducing valve operative to maintain a reduced substantially constant outlet pressure, a throttle valve, means for supplying steam under full boiler pressure to said reducing valve and for conducting steam from the outlet side thereof under reduced pressure to said throttle valve whereby said throttle valve is maintained completely full of steam under reduced pressure at all times so that a full volume of low pressure steam can be instantly supplied to said cylinders, means for conducting steam from the throttle valve to the engine cylinders, and means for supplying steam under full boiler pressure to said engine cylinders after the reduced pressure steam is initially supplied thereto.

2. In combination, a steam locomotive having a high pressure boiler and simple expansion cylinders, a transversely extending throttle valve casing having a plurality of throttle valve chambers and a common outlet therefor leading to the engine cylinders, a plurality of throttle valves in each of said chambers for variably controlling flow of steam therefrom to said outlet, means for supplying boiler steam directly to one of said throttle chambers, an outlet at one side of said casing communicating with said boiler steam supply means, a constant pressure outlet reducing valve communicating with said side outlet, and

means located at the other side of said throttle casing for connecting said reducing valve with the other one of said throttle chambers, whereby boiler steam is first supplied to said reducing valve and then to said latter throttle valve chamber which is thereby maintained completely full of steam under reduced pressure at all times so that a full volume of low pressure steam can be instantly supplied to said outlet.

3. In combination, a steam locomotive having a high pressure boiler and simple expansion engine cylinders, a throttle valve casing having a plurality of throttle valve chambers connected to the engine cylinders, a plurality of throttle valves in each of said chambers for variably controlling flow of steam therefrom to said engine cylinders, means for supplying full pressure boiler steam directly to one of said throttle chambers, a constant pressure outlet reducing valve communicating with said throttle chamber to which full boiler pressure steam is supplied, and means connecting the outlet side of said reducing valve with the other one of said throttle chambers whereby boiler steam is first supplied to said reducing valve and then to said latter throttle valve chamber which is thereby maintained completely full of steam under reduced pressure at all times so that a full volume of low pressure steam can be instantly supplied to said outlet.

4. In combination, a steam locomotive having a high pressure boiler and simple expansion cylinders, a transversely extending throttle valve casing having a plurality of transversely extending valve chambers, transversely extending chambers beneath each of said valve chambers and terminating in a centrally disposed longitudinally extending common outlet leading to the engine cylinders, a plurality of sequentially operated throttle valves in each of said throttle valve chambers for variably controlling flow of steam therefrom to said outlet, a main steam supply header having a steam pipe passage at one end and a steam supply chamber at its other end extending transversely of said throttle valve casing adjacent to and communicating directly with one of said throttle valve chambers whereby full boiler pressure steam can be supplied to said outlet, a constant pressure outlet reducing valve communicating with said header and throttle valve chamber to which full boiler pressure steam is supplied, and means connecting said reducing valve with the other one of said throttle valve chambers whereby boiler steam is first supplied to said reducing valve and then to said latter throttle valve chamber which is thereby maintained completely full of steam under reduced pressure at all times so that a full volume of low pressure steam can be instantly supplied to said outlet.

JAMES C. MARIS.
